UNITED STATES PATENT OFFICE.

AUGUSTUS O. THOMAS, OF KEARNEY, NEBRASKA.

GANG-MOLD

No. 877,140.

Specification of Letters Patent. Patented Jan. 21, 1908.

Application filed March 10, 1906. Serial No. 305,281.

To all whom it may concern:

Be it known that I, AUGUSTUS O. THOMAS, a citizen of the United States, residing at Kearney, in the county of Buffalo and State 5 of Nebraska, have invented certain new and useful Improvements in Gang - Molds, of which the following is a specification.

My invention relates to gang molds and has for its object the provision of a device of 10 this character adapted to mold a considerable number of Z shaped building blocks at a single operation.

A further object of the invention is the provision of a mold such as described, the parts 15 of which may be readily assembled or taken apart when desired.

Further objects and advantages of the invention will be set forth in the detailed description which now follows:

20 In the accompanying drawing: Figure 1 is a plan view of a gang mold constructed in accordance with the invention. Fig. 2 is a plan view of a portion of a gang mold. Fig. 3 is a detail perspective view of a skeleton end 25 plug hereinafter described. Fig. 4 is a detail perspective view of a solid end plug hereinafter described. Fig. 5 is a horizontal section through a portion of the mold, and Fig. 6 is a transverse section upon line 6—6 of 30 Fig. 2.

Like numerals designate corresponding parts in all the figures of the drawing.

Referring to the drawing the numerals 5 and 6 designate the side walls of the mold 35 and the numerals 7 and 8 designate the end walls of the mold. The end walls of the mold are rabbeted as at 9 to receive the ends of the side walls. A plurality of Z shaped pallets 10 are diagonally disposed between the side 40 walls 5 and 6 of the mold and have their ends beveled as at 11 in such manner that the ends of the pallets will rest flush against the side walls 5 and 6. The pallets 10 are spaced from each other by plugs 12. These plugs 45 are shown in Figs. 1, 4 and 5 as solid members. When placed between the pallets the side walls 13 of the plugs 12 rest flush against the pallets 10.

The walls of the plugs 12 which rest against 50 the side walls 5 and 6 of the mold are beveled as at 14 in such manner as to rest flush against said side walls of the mold while the

opposite walls 15 of said plugs are formed at right-angles to the walls 13 thereof, and consequently at right angles to the walls of the 55 pallets 10, whereby square ends will be provided upon the mold blocks which are formed by plastic material being placed in the mold spaces 16.

As is illustrated in Figs. 2 and 3 skeleton 60 end plugs may be substituted for those shown in Figs. 1, 4 and 5 if desired. These plugs comprise angle plates having the walls 17 and 18 disposed at right-angles to each other the edges of the walls 18 being beveled as at 65 19 in such manner that when the plugs are placed in position with the walls 18 lying flush against one of the pallets 10 and with the square end 20 of wall 17 resting flush against the edge of an adjacent pallet the 70 beveled portions 19 of wall 18 will rest flush against the side walls of the mold.

Clamps 21 having depending members 22 formed upon the ends thereof are adapted to bind the side walls of the mold together and 75 to hold the ends of said side walls so closely in engagement with the inner walls of the rabbets 9 that the mold will retain its form as long as said clamps 21 are in position.

The operation of the device is as follows: 80 The parts of the mold having been assembled as shown in Fig. 1 the mold spaces 16 are filled with plastic material which immediately begins to harden. The clamps 21 are then immediately removed as are also the side walls 85 and end walls. The end plugs are however, left in position until a more thorough setting of the material takes place, after which the end plugs may also be removed. The pallets are left in position until the blocks have 90 become thoroughly set.

From the foregoing description it will be seen that simple and efficient means are herein provided whereby a large number of building blocks of this peculiar shape may be 95 molded at a single operation. It will also be seen that a mold for building blocks is provided which may be readily assembled or taken apart.

While the elements herein shown and de- 100 scribed are well adapted to serve the purpose for which they are intended, it is to be understood that the invention is not limited to the precise construction set forth, but includes

within its purview such changes as may be made within the scope of the appended claims.

Having described my invention, what I claim is:

A mold comprising separable side and end walls, a plurality of Z-shaped pallets slantingly arranged between the side walls of the mold, a plurality of skeleton spacing members for spacing said pallets apart and having

beveled outer walls adapted to lie parallel with the side walls of the mold and having inner walls, forming the ends of the mold, arranged at right angles to said pallet.

In testimony whereof, I affix my signature 15 in presence of two witnesses.

AUGUSTUS O. THOMAS.
